UNITED STATES PATENT OFFICE

161,922

REFRIGERATED DISPLAY AND SERVE-SELF
CASE

David J. Greiling and Wallace R. Howard, Kendallville, Ind., assignors to McCray Refrigerator Company, Kendallville, Ind., a corporation of Indiana

Application July 27, 1950, Serial No. 11,434

Term of patent 7 years
(Cl. D80—11)

To all whom it may concern:

Be it known that we, David J. Greiling and Wallace R. Howard, citizens of the United States, and residents of Kendallville, in the county of Noble and State of Indiana, have invented a new, original, and ornamental Design for a Refrigerated Display and Serve-Self Case, of which the following is a specification, reference being had to the accompanying drawing, forming a part thereof.

In the drawing, Fig. 1 is a front perspective view of a refrigerated display and serve-self case, showing our new design; Fig. 2 is a rear view thereof, and Fig. 3 is an end view thereof, both ends having the same appearance.

The dominant features of our new design are shown in full lines.

We claim:

The ornamental design for a refrigerated display and serve-self case, substantially as shown and described.

DAVID J. GREILING.
WALLACE R. HOWARD.
